Primary Examiner — Paula Greene(74) *Attorney, Agent, or Firm* — TraskBritt(57) **CLAIM**

The ornamental design for a headphone, as shown and described.

DESCRIPTION

FIG. 1 is a perspective view of a first embodiment of a headphone;

FIG. 2 is a right side view of the headphone shown in FIG. 1; FIG. 3 is a left side view of the headphone shown in FIG. 1; FIG. 4 is a back view of the headphone shown in FIG. 1; FIG. 5 is a front view of the headphone shown in FIG. 1; FIG. 6 is a top view of the headphone shown in FIG. 1; and, FIG. 7 is a bottom view of the headphone shown in FIG. 1. The broken lines in FIGS. 1-7 are for environmental purposes only and do not fault any part of the claimed design.
